COMBINED VANITY AND MAKE-UP CASE

Robert A. Sanford, 27267 Clairview, Dearborn Heights, Mich. 48127

Filed Oct. 9, 1967, Ser. No. 8,926

Term of patent 7 years

(Cl. D86—10)

FIG. 1

FIG. 2

FIG. 3

I claim:

The ornamental design for a combined vanity and make-up case, as shown and described.
